UNITED STATES PATENT OFFICE

OSCAR S. FIELD, OF ROCHESTER, NEW YORK, ASSIGNOR TO GENERAL RAILWAY SIGNAL COMPANY, OF ROCHESTER, NEW YORK

INTERLOCKING DEVICE FOR RAILROADS

Application filed August 13, 1929. Serial No. 325,124.

This invention relates to railroad interlocking devices and more particularly to electric lever locks.

In one form of interlocking machine, the 5 tappet bar operated by each control lever to accomplish the mechanical interlocking between levers, is controlled by the action of the associated lever latch. Each time the lever latch is actuated, the lever is released for 10 movement, and the tappet bar is controlled to an intermediate position; but when the lever is in either extreme position and the lever latch associated therewith is released, the lever is locked from movement and the 15 tappet bar is controlled to a corresponding extreme position. This arrangement is commonly known as "latch locking", and assures that no opposing lever movement has been initiated, also that the mechanical locking 20 between levers may not be forced by pressure applied to the control lever.

It has been proposed to further protect train operation by the provision of an electric lock governing the movement of each 25 lever with which it is associated, which lock shall be dependent upon the conditions of the trackway associated therewith for its actuation to a releasing position. It is further proposed that such a lock shall be provided 30 with means for mechanically forcing its locking member to an engaging position each time the lever latch, of its associated control lever is released, thus assuring the proper operation of the lock at all times.

35 One object of the present invention is to provide an improved construction of an electric lock of the type described for latch locked interlocking levers, so that the electric lock is compact, may be cheaply manufactured, easily inspected or repaired, and affords the desired safety.

40 Other objects, purposes and characteristic features will in part be obvious from the accompanying drawings and in part pointed out as a description of the invention progresses.

45 In describing the invention in detail, reference will be made to the accompanying drawings, in which:—

50 Fig. 1 shows a side elevation of an electric

lever lock as included within the present invention, associated with a lever of an interlocking machine;

55 Fig. 2 shows a side elevation of the electric lever lock as included within the present invention with certain parts shown in section;

60 Fig. 3 shows a section of the electric lever lock as included within the present invention being taken on line 3—3 of Fig. 2;

65 Fig. 4 shows a section of the electric lever lock as included within the present invention being taken on line 4—4 of Fig. 2.

70 With reference to Fig. 1 of the accompanying drawings, a standard type interlocking lever L is shown having associated therewith an electric lever lock EL constructed in accordance with the present invention. The lever L is pivotally mounted on a shaft 5 supported by the legs 6 of the interlocking machine in the usual way. A lever latch handle 7 is pivoted on the lever L and is connected by a rod 4 to a latch dog 8 and a rocker die 10 which are pressed down by a spring 3. The latch dog 8 engages with shoulders 75 on the fixed quadrant 9 when said lever L is in extreme positions while the die 10 slides in a curved slot 11^a within a rocker link 11. The slot 11^a forms an arc having a radius 80 extending from the axis of the shaft 5. The rocker link 11 is pivoted at a point 12 and has pivotally attached thereto at one end a rod 13 which is connected to a tappet bar of 85 mechanical interlocking between levers in the usual manner.

90 The electric lever lock EL has a locking plunger or locking bar 14 which is operatively connected to the lever L by pivoted connecting links 15. The electric lever lock EL also has a circuit controller operated by 95 the action of the lever latch handle 7. This circuit controller is connected through a rod 16 to the rocker link 11.

95 The lever L has rigidly connected thereto the usual cross levers or tail levers 17 and 18 for controlling the traffic controlling devices associated therewith.

100 With reference to Fig. 2 of the drawings, the electric lever lock EL is shown as provided with a lower casing member 20 and an

upper casing member 21. These casing members 20 and 21 are suitably attached together in a manner to inclose the locking bar 14 and a cam bar 22. This locking bar 14 is slidably mounted within the lower casing member 20 between certain projections 20^a and 20^b (see Fig. 3), which projections form an integral part of the casing member 20. The cam member 22 is mounted above the locking bar 14 and adjacent thereto being held in position by projections 21^a and 21^b (see Fig. 2) which have suitable guiding slots therein. These projections 21^a and 21^b are integral with the casing member 21.

Above the inclosed locking chamber is mounted the actuating solenoid of the electric lock. This solenoid combination includes a coil 23, a brass or other non-magnetic metal lining 24, and a plunger 25. Mounted to the plunger 25 at the lower end is a web member 26 which passes around or over the cam bar 22 (see Fig. 3) being rigidly attached to a locking dog 27. This locking dog 27 is provided to enter suitable locking recesses 14^a and 14^b within the locking bar 14. The cam member 22 also has a retaining recess 22^a for permitting the upward movement of the lock dog 27 when said recess 22^a is adjacent either the locking recess 14^a or 14^b. The projections 20^a and 20^b are provided with suitable guiding slots 20^c to prevent any horizontal motion (see Fig. 2) of the locking dog 27 when engaged by the locking bar 14.

At the upper end of the plunger 25, a rod 28 is mounted which passes through a core 33 and an aperture 29^a (preferably oversized) in a lock plate 29. The core 33 is mounted in a cover 34 which incloses the coil 23 except at an opening left so that the coil leads may be taken to a terminal block.

The lock plate 29 is pivotally mounted at one side by a screw 30 and is biased toward an off center position by an anchored coil spring 31, whereby, if this bias is not counteracted by means other than the rod 28, the rod 28 cannot easily slide in the aperture 29^a. However, this plate 29 is held in a central position, so that the rod 28 may normally freely slide in the aperture 29^a, by a cover member 32 having an inwardly projecting retaining lug 32^a, when properly placed in position and can be locked therein by suitable means. In case the coil 23 fails to be energized, this arrangement permits the operator to manually raise or actuate the plunger 25, which position is maintained, while he operates the lever L, by the friction produced on the rod 28 with the lock plate 29 being biased toward an off center position when the cover 32 is removed. In other words, the plunger 25 may be said to be passively maintained in an actuated position by the binding effect of the lock plate 29, but not actively locked as the cam member 22 can still force the associated lock dog 27 into a locking

position when the lever latch handle 7 is released.

A crank member 35 is pivotally supported by the frame 21 upon a pin 36. This crank member has attached thereto a circular contact 37 mounted upon suitable insulating material, and which engages a pair of fixed contact members 38 and 39 which are suitably mounted to a terminal block 40.

The crank member 35 is connected to the rocker link 11 by the connecting rod 16 as heretofore mentioned.

In the movement of crank member 35 upon the pivot point 36, the cam member 22 is slidably operated, as pin 41, which is attached to said cam member 22, slidably engages the crank member 35 within suitable slots provided therein.

When the lever L is in either extreme position and the lever latch is released, the rocker link 11 is operated to a normal or a reverse position corresponding to the normal and reverse positions assumed by the lever L. Such operation of the control lever L, lever latch handle 7, the associated mechanical interlocking between levers, and the traffic controlling function operated by the control lever L, is well understood by those skilled in the art and need not be explained in detail.

As the crank member 35 is operably connected to the rocker link 11 by the connecting rod 16, it too will assume a normal non-contacting position as shown, an intermediate contacting position so that the contact 37 will interconnect the fixed contacts 38 and 39, and also a reverse non-contacting position. The reverse non-contacting position is provided for by a recess 40^a within the terminal block 40 which allows the contact 37 to pass to the right of the fixed contacts 38 and 39 (see Fig. 4).

With the crank member 35 assuming any one of its three positions, obviously the cam member 22 must likewise assume corresponding positions as it is slidably operated within the guiding slots provided in the projections 21^a and 21^b. When the cam member 22 is in its intermediate position, the retaining recess 22^a is opposite the lock dog 27 which permits the actuation of said lock dog 27 to a non-engaging position in respect to the locking bar 14.

Let us assume that the operator desires to move the lever L from its present extreme normal position to an extreme reverse position. To do this he actuates the lever latch handle 7, thus disengaging the latch dog 8 from the quadrant 9 and actuates the crank member 35 to an intermediate contacting position. With the crank member 35 in an intermediate position, the cam member 22 has also been operated to an intermediate position so that the retaining slot 22^a is adjacent to the locking recess 14^a. Also, the contact 37

electrically interconnects the fixed contacts 38 and 39 which closes a suitable circuit for the solenoid coil 23, providing the track section associated therewith is unoccupied. Thus, the plunger 25 is actuated to an upper extreme position, in which position the lock dog 27 is within the retaining recess 22^a allowing the movement of the lever L to a reverse extreme position.

10 When the lever L has been operated to a reverse extreme position, the locking recess 14^b is beneath the retaining recess 22^a so that as the lever latch handle 7 is released and the coil 23 deenergized, the lock dog 27 is forced 15 into the locking recess 14^b by the inclined surfaces of the retaining recess 22^a as the cam member 22 moves in a left hand direction towards its extreme left hand position. Also, should the coil 23 remain energized for some 20 undesirable reason, when the lever latch handle 7 is released, the lock dog 27 would still be forced into a locking position by the cam member 22.

25 The operation of the lever L from a reverse position to a normal position is an inverse function of the operation above explained.

With this arrangement as above explained, the release of the lever latch handle 7, when the lever L is in either extreme position, mechanically forces the lock dog 27 into engagement with the lock bar 14. However, if either of the locking recesses 14^a and 14^b are not in proper positions due to lost motion or other causes affecting the position of the lever L, then the lock dog 27 can not be forced down by the cam member 22. This results in the lever L being incapable of being latched, which prevents the movement of the tappet bar associated with this lever to be moved to its extreme position, thus preventing opposing lever movements until the defect is remedied.

It should be noted that the lock bar 14 may vary in size and length, and also the number of locking notches, and their size and shape may vary to a considerable extent according to the various conditions to be met in the practice of well known interlocking principles. It should further be noted that the size of the lock dog 27 may vary according to the stresses which are to be placed upon it.

With the circuit of the coil 23 being governed by the lever latch, considerable energy is saved in that it is not energized except at such times that the lock dog 27 is to be actuated to a non-engaging position.

An electric lock peculiarly adaptable for latch locked interlocking levers has been described. This electric lock, as an embodiment 60 of the present invention, is compact in size and form, efficient and safe in operation.

An electric lock as one specific embodiment of the present invention has been described to facilitate the disclosure and explanation of 65 the nature of the invention, and it is to be un-

derstood that the various modifications and adaptations which may be applied to such an electric lock so that it will meet the requirements of various operating conditions, are to be included within the present invention such as come within the scope of the appended claims.

Having described my invention, I now claim:

1. In an electric lock for interlocking control levers, means locking said control lever except when actuated, means capable of actuating said locking means, cover means normally positioned to prevent manual actuation of said locking means, means passively maintaining said locking means actuated when said cover means is not normally positioned.

2. In an electric lock for interlocking control levers, a lock plunger operated by a control lever, a locking dog engaging said lock plunger to restrict its movement, a magnet plunger connected to said locking dog, a solenoid magnet capable of actuating said magnet plunger, contact means controlling said solenoid magnet, means inclosing said contact means, and means permitting manual actuating of said magnet plunger when said inclosing means is not in a normal inclosing position.

3. In an electric lock for interlocking control levers, a lock plunger operated by a control lever, locking means capable of preventing movement of said lock plunger except when actuated, electro-magnet means capable of actuating said locking means, contact means governing the operation of said electro-magnet means, cover means inclosing said contact means and preventing unauthorized manual manipulation, and means permitting manual actuation of said locking means when said cover means is removed.

4. In an electric lock for interlocking control levers, a lock plunger operated by a control lever, a locking means capable of preventing movement of said lock plunger except when actuated, electro-magnet means capable of actuating said locking means, contact means governing the operation of said electro-magnet means, cover means inclosing said contact means and preventing unauthorized manual manipulation, and lock means passively maintaining manual actuation of said locking means including a spring biased plate having an aperture, being normally detained from its biased position by said cover means, a plunger operably controlled by said locking means and normally freely passing through said aperture of said spring biased plate when said locking means is actuated, and abnormally prevented from freely passing through said aperture when said spring biased plate is in a biased position.

5. In an electric lock for interlocking levers, a slidably operable lock bar, a pivoted link means connecting said lock bar with an

interlocking lever, a slidably operable cam bar adjacent to said lock bar and operably controlled by a lever latch handle, a lock dog between said lock bar and said cam bar actively preventing movement of said lock bar except when actuated, an electro-magnet, an armature capable of being operated by said electro-magnet, a web member rigidly connecting said lock dog to said armature with said web allowing the passage of said cam bar between said armature and said lock dog, circuit controlling means associated with said electro-magnet, cover means normally in a predetermined position for protecting said circuit controlling means, and preventing manual actuation of said lock dog, and a lock means passively maintaining actuation of said lock dog when said cover means is not normally positioned.

20 6. In an electric lock for interlocking levers, a solenoid actuating means with circuit controlling means associated therewith, a plunger controlled to an extreme position by actuation of said solenoid, a lock dog, a web member rigidly connecting said lock dog to said plunger, a locking member having a recess to receive said lock dog at which time said locking member is prevented from movement, a cam member passed through said web member and actively forcing said lock dog to engage said locking member when said cam member is controlled to either of two extreme positions and passively allowing said lock dog to be disengaged from said locking member when said solenoid is energized and said cam member is in an intermediate position.

7. In an electric lock for interlocking control levers, a two part casing, a locking bar slidably mounted within said casing and operably connected to a control lever, a cam member slidably mounted adjacent to said locking bar, a locking dog mounted between said locking bar and said cam member within a locking recess in said lock bar, actuating means rigidly connected to said lock dog by a web member passing over said cam member and mounted above said locking bar and said cam member, whereby the movement of said control lever is governed in accordance with said actuating means.

8. In an electric lock for interlocking control levers, a lock plunger operably connected with a control lever and capable of assuming either of two extreme positions, a cam plunger slidably engaging said lock plunger and operable to either of two extreme positions or to an intermediate position by a lever latch handle, two locking recesses in said lock plunger, a retaining recess in said cam plunger, mounting means slidably supporting said lock plunger and said cam plunger, a lock dog actively engaging said mounting means and preventing movement of said lock plunger from either extreme position with said cam plunger in either extreme position,

and means for actuating said lock dog into said retaining recess when said cam plunger is in an intermediate position releasing said lock plunger.

In testimony whereof I affix my signature. 70
